UNITED STATES PATENT OFFICE.

FRANCIS M. MOSHER, OF CANTON, ILLINOIS.

DESIGN FOR A TOOL OR IMPLEMENT RACK.

41,993.

Specification for Design.

Patented Dec. 19, 1911.

Application filed May 8, 1911. Serial No. 625,902. Term of patent 14 years.

To all whom it may concern:

Be it known that I, FRANCIS M. MOSHER, a citizen of the United States, residing at Canton, in the county of Fulton and State of Illinois, have invented a new, original, and ornamental Design for Tool or Implement Racks, of which the following is a specification, reference being had to the accompanying drawing, forming part thereof.

The figure is a perspective view of a tool

or implement rack, showing my new design.

What I claim is:

The ornamental design for a tool or implement rack, as shown.

FRANCIS M. MOSHER.

Witnesses:

HENRY C. OLDS,
GEO. M. HELLER.
